(57) **CLAIM**

The ornamental design for a note dispenser, as shown and described.

DESCRIPTION

FIG. 1 is a front view of a note dispenser showing the new design;

FIG. 2 is a back view thereof;

FIG. 3 is a left side view thereof;

FIG. 4 is a right side view thereof;

FIG. 5 is a top view thereof; and,

FIG. 6 is a bottom view thereof.

The portions of the note dispenser in FIGS. 1-6 shown in broken lines are included to show features that form no part of the claimed design.
